UNITED STATES PATENT OFFICE.

THOMAS W. G. COOK, OF NEW YORK, N. Y., ASSIGNOR TO CHARLES AYERS & CO., OF SAME PLACE.

DESIGN FOR A CLAMP-BAND.

SPECIFICATION forming part of Design No. 31,895, dated November 28, 1899.

Application filed November 2, 1899. Serial No. 735,640. Term of patent 7 years.

To all whom it may concern:

Be it known that I, THOMAS W. G. COOK, a citizen of the United States, residing in the city of New York, borough of Manhattan, in 5 the county and State of New York, have invented and produced a new and original Design for a Clamp-Band, of which the following is a full, clear, and exact specification.

Reference is to be had to the accompanying 10 drawing, forming a part of this specification, in which the figure is a perspective view of a clamp-band, showing my design.

The design in its entirety consists of a band A, appearing in circular shape and having outwardly-turned apertured flanges B B' at the 15 ends, the middle portion of the band appearing with a longitudinally-extending bar C and

with outwardly set-off bars D D', all merging at their ends in the band A, the latter appearing with similar bars C D D' near the 20 flange B.

The leading feature of the design consists of the flanged band with the set of bars C D D'.

Having thus fully described my invention, 25 I claim as new and desire to secure by Letters Patent—

The design for a clamp-band herein shown and described.

THOMAS W. G. COOK.
